CLAIM

I claim the ornamental design for a modular display unit, as shown and described.

DESCRIPTION

FIG. 1 is a front perspective view of a modular display unit showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is a front perspective view of the modular display unit provided with an additional unit to show state of use when two units are combined.

The evenly-dashed broken lines in the figures depicting portions of the modular display form no part of the claimed design.

The dot-dash broken lines showing the additional unit in FIG. 9 are for environmental purposes only and form no part of the claimed design.
